United States Patent

Des. 237,137
Patented Oct. 14, 1975

237,137

FIREPLACE SCREEN

Floyd R. Clark, 9014 N. Richmond Ave.,
Portland, Oreg. 97203

Filed Nov. 8, 1973, Ser. No. 414,610

Term of patent 14 years

Int. Cl. D7—08

U.S. Cl. D7—208

Fig. 1.

Fig. 2.

FIG. 3.

FIG. 4.

FIG. 5.

FIG. 1 is a front elevational view of a fireplace screen showing my new design, an enlarged detail of the pattern of the stippled area is seen in FIG. 5;

FIG. 2 is a view in rear elevation thereof;

FIG. 3 is a top plan view thereof;

FIG. 4 is a view in side elevation thereof; and

FIG. 5 is a fragmentary front elevation showing on an enlarged scale the design character of the stippled portions of FIG. 1.

I claim:

The ornamental design for a fireplace screen, as shown.
